UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

YARN-SPINNING APPARATUS.

No. 798,704.

Specification of Letters Patent.

Patented Sept. 5, 1905.

Application filed May 1, 1905. Serial No. 258,184.

To all whom it may concern:

Be it known that I, ALONZO E. RHOADES, a citizen of the United States, and a resident of Hopedale, in the county of Worcester and State of Massachusetts, have invented an Improvement in Yarn-Spinning Apparatus, of which the following description, in connection with the accompanying drawings, is a specification, like characters on the drawings representing like parts.

This invention relates more particularly to apparatus adapted to effect the winding of yarn upon a yarn-receiver or bobbin in such manner that a preliminary winding or bunch is first laid and thereafter a main or service winding is laid. Yarn-receivers so wound are subsequently used in the shuttles of automatic filling-replenishing "feeler-looms," a feeler acting to cause a change of filling when the yarn has been woven off down to the preliminary winding, the latter still containing sufficient yarn to last while the change is being made.

I have previously obtained two United States Patents for apparatus of the character above specified, No. 686,906, dated November 19, 1901, and No. 722,145, dated March 3, 1903, the ring-rail being given a short traverse during the formation of the bunch, and the traverse is then lengthened automatically to lay the main or service winding. Both forms of patented apparatus employ a reciprocating carriage included in the operating connections between the ring-rail and the builder-motion, and such carriage and the portion of the apparatus adjacent thereto carry the means to control automatically the builder-motion and effect the change of traverse.

In my present invention I have dispensed with the carriage altogether, and the traverse shifting and controlling means is constructed practically as a part of the builder-motion, thereby obviating the employment of separate mechanism necessary in the patented apparatus.

The change or shifting of the traverse is effected automatically in the present embodiment of my invention, and I have provided novel means whereby the volume of the preliminary winding can be regulated very accurately and readily. I have also so constructed the apparatus that after doffing and winding back have been effected the parts will be

in readiness to begin the preliminary or bunch winding on a new set of yarn-receivers when the frame is started.

The apparatus can be utilized for plain winding—that is, without the formation of the bunch—by throwing into a different position a single member of the apparatus, the return of such member to its usual position setting the apparatus for bunch-winding.

The various novel features of my invention will be fully described in the subjoined specification and particularly pointed out in the following claims.

Figure 1 is a front elevation of a portion of a spinning-frame having applied thereto one embodiment of my present invention, the parts being shown in position to lay the preliminary or bunch winding. Fig. 1^a is a detail of the ring-rail downhold to be described. Fig. 2 is a transverse sectional view on the line 2-2, Fig. 1, looking toward the left, the builder-motion being shown as just about to effect the downward stroke of the ring-rail. Fig. 3 is a top plan view of the main portion of builder-motion, other parts of the apparatus being omitted to avoid confusion. Fig. 4 is a transverse sectional detail on the line 4-4, Fig. 1, looking toward the right and omitting the actuating or traverse cam, a part of the mechanism being broken out and shown in section. Fig. 5 is a view similar to Fig. 2, showing some of the mechanism therein illustrated, but with such mechanism in condition to effect the main or service winding. Fig. 6 is an enlarged detail in plan of the member of the builder-motion which carries the winding mechanism and which also is the member through which short traverse is effected. Fig. 7 is a side elevation of the parts shown in Fig. 6. Fig. 8 is a right-hand end elevation of the builder member shown in Figs. 6 and 7, the winding-drum being omitted. Fig. 9 is an enlarged detail, in side elevation and partial section, of a part of the mechanism for controlling the length of traverse, the said part being broken out between its ends to save space. Fig. 10 is an enlarged side elevation of a bobbin with the completed preliminary winding or bunch thereon and with the ring-rail in dotted lines at the lowest point of its traverse and ready to ascend to begin the main winding with the full traverse. Fig. 11 is a side elevation of the key for wind-

100
105

ing back, and Fig. 12 is a transverse section thereof.

In the earlier of the two patents referred to the ring-rail is raised by means of a lifting-weight and depressed by or through the builder-motion, the drum of the winding mechanism thereof being gradually unwound to effect the "gain" of the traverse by letting off the chain little by little as the yarn is laid upon the yarn-receiver. My present invention is shown as applied to a frame of similar construction and operation, though its use is not restricted thereto, as will be manifest to those skilled in the art. It will be understood that the gradual unwinding of the chain secured at one end of the drum and connected indirectly with the ring-rail effects the gain of the traverse, whereby at each up-stroke the ring-rail rises a little higher and at each downstroke descends not quite so low as on the previous downstroke to lay the yarn in successive layers upon the bobbin from the lower end or base thereof to the upper end.

In Figs. 1 and 2 the spindle-rail 1, on which are mounted rotatable spindles 2 of the sleeve-whirl type, as herein shown, the vertically-reciprocating ring-rail 3, provided with rings 4, one for each spindle, the usual lifter-rods 5, only one being shown in Fig. 1, the rocker 6, coöperating with the foot of the lifter-rod and provided with a weight 7 to elevate the ring-rail, and the upturned rocker-arm 8, rigidly connected with the rocker and transmitting reciprocating movement to the other lifter-rods through the link 9, may be and are all substantially of well-known or usual construction in spinning or similar apparatus. The end of the rocker 6 is extended beyond the foot of the lifter-rod to form a pedal or foot-piece 10, Fig. 1, and an upturned arm 11, shouldered at 12, Fig. 1^a, is fulcrumed at 13 on the rocker and provided with a lateral foot-piece 14, the arm constituting a down-hold for the ring-rail when the shoulder 12 is brought under the longitudinal girth 15 of the main frame. Under normal conditions the downhold rises and falls with the oscillatory movement of the rocker 6, the shoulder never descending low enough to catch under the lower edge of the girth 15; but when the operator wishes to depress the ring-rail, as for doffing, he places his foot on the foot-piece 14 and presses down the rocker until the shoulder 12 passes under the girth. Thereupon the weight 7 will hold the shoulder and girth in engagement with the ring-rail in doffing position, and to release the ring-rail the foot-piece 10 is depressed, permitting the weight 16 of the downhold to swing it back away from the girth into the position shown in Figs. 1 and 1^a, thereby freeing the ring-rail from control by the said downhold. The operation of this portion of the mechanism will be referred to hereinafter in connection with the change

from long to short traverse and the winding-back operation. The rocker 6 has a rigidly-connected arm 16, provided with a segmental upper end 17, to which is secured one end of a chain or other flexible connection 18, which passes over a fixedly-sustained guide-sheave 19, Fig. 1, and thence down to the winding mechanism to be referred to, the builder-motion acting through the chain to positively depress the ring-rail and permitting its ascent by the weight 7.

I have herein shown the builder-motion as including two connected rocking members movable in unison and also having a differential motion, one of said members being hereinafter termed the "builder-arm" and the other member the "traverse-shifter." The builder-arm 20, shown as an elongated bar, has at its inner end a long hub 21, Fig. 3, fulcrumed on a shaft 22, rigidly supported by the end frame 23 and an upright standard 24, Fig. 1, collars 25 on the shaft preventing end-wise movement of the hub, the latter having a radial brace 26 extended therefrom parallel with the arm 20 and connected therewith by a short fixed shaft 27. Said shaft enters a boss on the builder-arm, provided with an upturned guide-lug 28, Figs. 3 and 4, for a purpose to be described, the builder-arm being provided with a roller or other stud 29, constituting a follower to coöperate with a single actuator, shown as a traverse-cam 30, herein illustrated as a four-point cam, Fig. 5. The follower 29 is made adjustable on the builder-arm by means of the plate 31, bolted thereto, Fig. 4, and a guide-lug 32 is upturned from said plate above the top of the arm.

The short shaft 27 is near the center of the builder-arm and has loosely mounted upon it the hub 33 of the traverse-shifter, shown as an arm 34 extended in parallelism with and adjacent the builder-arm to its outer free end, said traverse-shifter having mounted upon it the winding mechanism of substantially usual construction. Said mechanism includes a drum 35, pick-shaft 36, provided with a worm 37 to effect gradual rotation of the drum, pick-wheel 38 on said shaft 36, Figs. 2 and 4, an actuating-pawl 39, operated in usual manner when long traverse is in action, and a second actuating-pawl 40, operated during short traverse. Rotation of the cam 30 oscillates or rocks the builder-arm 20 on its fulcrum 22 with a constant stroke, and a weight 41, (see Fig. 2,) attached to one end of a chain 42, which passes over guide-sheaves 43 44 and which is secured to the free end of the builder-arm, counterbalances the weight of the parts carried by the builder-arm and maintains the follower 29 in engagement with the actuating-cam 30.

The gradual unwinding of the chain 18 by rotation of the drum effects the gain of the traverse, as will be manifest, and when the long traverse is used the builder-arm 20 and

traverse-shifter 34 rock in unison on the fulcrum 22, and at such time the rotation of the drum is controlled by the pawl 39, Fig. 1; but when short traverse is used the traverse-shifter 34 rocks about a different and temporary fulcrum, to be described, its movement being so slight that the pawl 39 cannot then control the drum. Then the pawl 40, mounted on the depending arm 45 of a bracket 46, secured to the free end of the builder-arm, is called into action to control the gain, the relative movement of the adjacent portions of builder-arm and traverse-shifter being sufficient for the purpose. The bracket has an upturned arm 47, bent laterally across and above the builder-arm and provided with an upward extension 48 (see Fig. 1) for a purpose to be described.

It will be obvious that when the members 20 and 34 are coupled or locked to rock in unison on the fulcrum 22 the traverse of the ring-rail will correspond to and be directly controlled by the constant stroke imparted by the actuating-cam to the builder-arm, and this longer uniform traverse is employed to lay a main or service winding "*w*" on a yarn-receiver or bobbin "*m*". (See Fig. 10.) When, however, a preliminary winding or bunch "*m*" is laid upon the yarn-receiver, it is laid with a shorter uniform traverse, and in order to effect such short traverse the traverse-shifter 34 is rocked about a fulcrum different from that of the builder-arm and with a much shorter stroke than the latter. To this end a fulcrum member 49 50 is pivoted at 51 to the outer end of the traverse-shifter, the parts being adjustably connected by a bolt 52 to vary the position of the pivot 51, the latter being the fulcrum about which the traverse-shifter rocks during the short traverse or bunch-building period. A shoulder 53 on the fulcrum member is adapted when said member is operative to engage the under side of the girth 15, as shown in Figs. 1, 2, and 4, whereby the fulcrum member is held stationary by the action of the lifting-weight 7 exerted through the chain 18 upon the winding mechanism.

On the front end of the traverse-shifter is fulcrumed at 54 (see Figs. 6, 7, and 8) a transverse latch 55, having a rib 56 on its upper face at the side of its fulcrum nearer the builder-arm and a slot 57 in its opposite end, the slot receiving loosely the lower end of a pin 58, secured at its upper end in an ear 59 on the fulcrum member, a spring 60 being coiled around the pin between the ear and the latch. Beneath the latch the traverse-shifter is enlarged laterally to form stop-faces 61 62, Fig. 8, which permit a rocking movement of the latch and also act to limit such movement.

The center of gravity of the fulcrum member is so disposed with relation to the pivot 51 that said member tends to swing forward into position to coöperate with the girth 15 if the

spring 60 is uncompressed; but if said spring is compressed by movement of the latch into the position shown in Fig. 8 the expansion of the spring will swing the fulcrum member into inoperative position, Fig. 5, just as soon as the downstroke of the builder-arm carries down the outer end of the traverse-shifter, as will be explained, and the shoulder 53 is separated from the girth 15. When the fulcrum member is inoperative, a lug 63 thereon rests on a stop 64, rising from the traverse-shifter, (see Figs. 5, 7, and 8,) and so long as the latch is held against the stop-face 61 the spring 60 will be under sufficient compression to maintain the fulcrum member inoperatively positioned.

Referring momentarily to Fig. 2, it will be seen that when the fulcrum member is operatively positioned the outer end of the traverse-shifter 34 will be held practically stationary and its inner end will swing through an arc equal to the arc through which the short shaft 27 is moved by the constant stroke of the builder-arm. Inasmuch as this arc is much smaller than the arc of movement at the outer end of the builder-arm, it will be obvious that the amplitude of movement of the traverse-shifter will be very much less than that of the builder-arm, and consequently the traverse of the ring-rail will be correspondingly short to lay the preliminary or bunch winding of yarn. Such winding continues so long as the fulcrum member is in engagement with the girth 15, and I will now describe the means for automatically changing the latch 55 from the position shown in Fig. 1 to that shown in Figs. 5 to 8, inclusive, to thereby change from short to long traverse and shift from the bunch to the main or service winding of the yarn.

Upon the top of the builder-arm is mounted a sliding controlling device or latch-dog, shown separately in Fig. 9 as comprising two elongated members 65 66, longitudinally slotted at 65^x 66^x , respectively, and placed end to end, the part 66 having a housing 67 for a headed plunger 68, secured to the upturned end of the part 65, a strong spring 69 between the plunger-head and the inner end of the housing normally acting to pull the parts together, so that the two-part latch-dog will move as one piece. A transverse notch 70 in the under side of the part 66, near its front end, is adapted to at times receive the latch-rib 56, hereinbefore referred to, and the part 65 is provided with two ears 71 72 and with an upright shoulder 73 at or near its rear end. The latch-dog is longitudinally slideable along the top of the builder-arm and is held thereon and guided by headed studs 70^x , which pass loosely through the slots 65^x and 66^x into the builder-arm, the guide-lugs 28 and 32 also assisting in guiding the latch-dog. A short arm 74 on the hub 21 has fulcrumed upon it a detent 75, shaped to engage the shoulder 73 and retain the latch-dog in the

position shown in Figs. 2 and 4 against the action of an actuator, shown as a weighted lever 76, fulcrumed on the side of the builder-arm and having a short upturned finger 77, 5 adapted to engage a pin 78, extended laterally from the member 65 of the latch-dog. When the detent is disengaged from the shoulder 73, the weight of the actuator swings the finger 77 forward, and through the pin 78 the 10 latch-dog is moved forward until its front end projects above the ribbed portion of the latch 55 on the traverse-shifter, as in Fig. 5. When the latch-dog is thus moved forward, the next downward stroke of the builder-arm brings 15 the rib 56 into the notch 70 and turns the latch into the position shown in Fig. 8 against the stop-face 61 and compresses the spring 60. Consequently the latter by expanding when 20 the builder-arm carries down the outer end of the traverse-shifter returns the fulcrum member 49 50 to inoperative position, and the coöperation of the latch and latch-dog couples or locks the builder-arm and traverse-shifter together to oscillate in unison, and short traverse 25 is thus terminated and long traverse begun.

I have devised simple means to automatically release the latch-dog from control of the detent, and for such purpose the detent 75 is provided with a forward extension 79 in the 30 path of movement of a tripping-pin 80, projecting laterally from a controlling-ratchet 81, rotatably mounted on a stand 82, secured to the builder-arm near its fulcrum. The axle 83 of the ratchet has adjustably secured 35 to it by a set-screw 84, Fig. 3, a weighted arm 85, which tends to always return the ratchet to a definite position—viz., that shown in Figs. 2, 4, and 5—a pawl 86, fulcrumed on the ear 73 of the latch-dog, acting 40 at times to prevent rotation of the ratchet in the direction due to the action of said weighted arm. As the detent-pawl 86 is mounted on the latch-dog, movement of the latter into 45 operative position by the actuator 76 will disengage the pawl from the controlling-ratchet, as in Fig. 5. Step-by-step forward angular movement of the ratchet is effected by a pawl 87, pivoted on the rear end of an arm 88, fulcrumed on a stud 89, extended from the end 50 frame 23, the front end of the arm having depending from it a preferably adjustable foot 90. The foot is located in the path of the extension 48 of the bracket 46, secured to the front end of the builder-arm, and when 55 the latter rises the extension hits the foot and rocks the arm 88, depressing the pawl 87, and thereby advancing the ratchet 81 an angular distance constituting a step. Starting from the position shown in Fig. 4, then a 60 predetermined number of angular advances or steps of the ratchet will cause the tripping-pin 80 to engage the extension 79, and thereby lift the detent 75 from engagement with the shoulder 73, whereupon the latch-dog 65 66 will be moved forward into operative

position by the actuator 76. As each advance of the ratchet is equivalent to a stroke of the builder-arm and this is accompanied by an equal number of strokes of the traverse-shifter, it will be seen that the release of 70 the latch-dog is effected when a predetermined number of short-traverse strokes of the ring-rail have been made. By setting the pin 80 nearer to the detent extension 79 the release will be effected when a less number 75 of traverses have been made, and consequently when less yarn will have been laid in forming the bunch, so that by regulating the amount of angular movement of the ratchet the volume of yarn in the bunch is regulated. As the latch-dog is moved forward the detent-pawl 86 is disengaged from the ratchet 81, and the weighted arm 85 operates to return it to initial position, the descent of the outer end of the builder-arm permitting 80 the quick return of the ratchet to temporarily throw out the operating-pawl 87. It will be remembered that as soon as the latch-dog and latch 55 coöperate the builder-arm and traverse-shifter are coupled or locked together, and thereafter the traverse will be long, and the main or service winding *w'*, Fig. 10, will be laid, completing the winding.

The barrel of the bobbin *m*, Fig. 10, has near its head or base *m'* a portion *m''*, which is substantially cylindrical and technically termed the "feeler-wood," and upon this part the preliminary winding or bunch *w* is wound with the short uniform traverse, as has been described.

The completion of the winding by the service-winding is indicated at *w'* by dotted lines, Fig. 10, both windings being wound with the filling-wind, the gain of the traverse acting during each winding, as has been set forth.

Referring now to Figs. 6 and 7, the side of the drum 35 of the winding mechanism adjacent the traverse-shifter 34 has formed thereon a cam 91, shown as an incomplete circular rib, and a resetting-pawl 92 is fulcrumed on the ear 71 of the sliding latch-dog 65 66, said pawl having a depending tooth 93, which is arranged to coöperate with the cam 91. During the gradual unwinding of the chain 18 from the drum the tooth 93 will ride upon the cam 91, the rotation of the drum being indicated by the arrow, Fig. 7, and when the main or service winding has been completed the tooth will drop into the space between the two ends of the circular cam. When the winding-back operation is performed by the operator, the end 94 of the cam will engage the tooth, and as rotation of the drum is then opposite to the arrow, Fig. 7, the resetting-pawl 92 will be forced to the left, viewing said figure, and it will retract the part 65 of the latch-dog to the position shown in Fig. 4, the detent-pawl 75 automatically engaging the shoulder 73, and those parts will be reset. Let it be supposed that the winding of a set 125

of bobbins has been completed and that the ring-rail is at its highest position, while the tooth 93 is between the ends of the circular cam 91. The operator then depresses the 5 ring-rail by pressing down upon the foot-piece 14 until the shoulder 12 of the arm 11 catches under the girth 15, holding the rail down. Such downward movement of the ring-rail relieves the traverse-shifter 34 of the weight 10 of the counterbalance 7, slackening the chain 18, and the traverse-shifter is then free to swing downward on its pivotal connection 27 with the builder-arm, such downward swing withdrawing the ribbed end of the latch 55 15 from the notch 70 of the latch-dog, and the builder-arm and traverse-shifter are thereby unlocked or uncoupled. Now the operator "winds back," (either before or after doffing,) taking up the slack of the chain 18 on the 20 drum 35 as it is rotated oppositely to the arrow, Fig. 7, and at the same time causing the end 94 of the cam 91 to act upon the tooth 93 of the pawl 92, moving the latch-dog back or resetting it in the position shown in Fig. 4. 25 The spring 69 is strong enough to cause the part 66 of the dog to move back with the part 65, and as the latch-dog is caught the curved portion of the cam acts upon the projecting toe 95 of the pawl 92 and throws the 30 tooth out of engagement with the end 94 of the cam. When the latch-dog is thus withdrawn and reset, its notched forward end is moved back out of the path of the latch 55. Before starting up the frame the operator releases the downhold 11, so that the ring-rail 35 is returned to the control of the weight 7 prior to starting the formation of the bunch-winding on the fresh set of bobbins. The action of the weight 7 acts through the chain 40 18 to lift the free outer end of the traverse-shifter 34 until the shoulder 53 of the fulcrum member or dog 49 50 engages the girth 15, stopping further upward movement. The release of the latch from the latch-dog permits 45 the fulcrum member to swing forward on its pivot 51 into position to engage the girth when the outer end of the traverse-shifter is raised, as described.

If the foregoing operation were always followed, 50 the two-part construction of the latch-dog would be unnecessary; but such operation is varied by the operator winding back upon completion of the set of bobbins against the resistance of the counterbalance 7, such 55 resistance tending to keep the rib 56 of the latch in operative engagement with the notch 70 of the latch-dog, so that the builder-arm and traverse-shifter remain locked together. In such case the winding back causes the cam 60 91 to operate the resetting-pawl 92, as has been described, the part 65 of the latch-dog being reset; but as the part 66 is held from movement the spring 69 is compressed as the plunger 68 is drawn into the housing 67. The 65 operator doffs after completing the winding

back, and as the ring-rail is not low enough to permit doffing it must be still further depressed, and this is effected by means of the foot-piece 14, as before, the downhold 11 retaining the rail lowered for doffing; but this 70 acts as previously to relieve the traverse-shifter of the upward pull due to the counterbalance 7, and the traverse-shifter drops far enough to disengage the latch from the notched part 66 of the latch-dog. Instantly the compressed spring 69 expands and retracts the part 66 from the path of the latch and causes it to abut against the end of the previously-reset part 65, the fulcrum member on the traverse-shifter swinging into position ready 75 to coöperate with the girth 15, as before, on the next succeeding upward movement of the outer end of the traverse-shifter.

From the foregoing description of the two methods of handling the apparatus when the 80 winding of a set of bobbins has been completed it will be understood readily that if the first method of operation were always practiced there would be no necessity for the two-part construction of the sliding latch-dog and 85 the spring connection between them. In practicing the second method such structure is necessary, because the resetting-pawl is caused to operate while the front end of the latch-dog and the latch are locked together during 90 winding back. Should it be desired to utilize the apparatus for regular winding of the yarn upon the yarn-receivers or bobbins, the resetting-pawl is either thrown back out of coöperation with its controlling-cam or it can be 95 detached from the latch-dog, the latter then maintaining continuous engagement with the latch on the traverse-shifter. Such engagement serves to maintain the spring 60 under 100 sufficient compression to retain the fulcrum member 49 50 in inoperative position. (Shown in Fig. 5.)

When winding back, the operator applies a suitable key to the pick-shaft 36, the front end of the latter having a socket 96, Fig. 1, to receive the end 97 of the key, Figs. 11 and 12 in the present construction, and the key is shown as having a circular head 98, provided with an annular beveled flange 99 and a handle 100. When the key is applied, the beveled edge of the flange passes under and disengages the two pick-pawls 39 and 40 from the pick-wheel 38, so that the said pawls will slide over the flange as the winding back is effected. 110

The mechanism for automatically shifting from short to long traverse and for controlling the time during which short traverse is effective are all practically included as a part of the builder-motion and are carried by the 115 builder-arm, the construction eliminating the employment of a reciprocating carriage and parts carried thereby, as in earlier structures invented by me and referred to hereinbefore.

By slightly taking up or letting off the chain 120

18 in the usual manner the position of the ring-rail can be varied to change the position of the bunch-winding, and the same result can also be attained by adjustment of the two parts 5 of the fulcrum member or dog one relatively to the other.

A variation can be made in the length of traverse, both short and long, by adjustment of the follower on the builder-arm, an increased stroke being effected by adjustment toward the builder-arm fulcrum and a decreased stroke by adjustment of the follower in the opposite direction.

My invention is not restricted to the precise 15 construction and arrangement herein shown and described, as the same may be varied or modified in different particulars by those skilled in the art without departing from the spirit and scope of my invention.

20 Having fully described my invention, what I claim as new, and desire to secure by Letters Patent, is—

1. In apparatus of the class described, a builder-motion, including a builder-arm having a constant stroke, and means carried by said arm to control the builder-motion and effect automatically the formation of a preliminary winding, and thereafter a main winding, of yarn upon a yarn-receiver.

25 2. In apparatus of the class described, a builder-motion, including an oscillating member having a constant stroke, and means carried by said member to control the builder-motion and through it effect automatically the 30 formation of two successive windings of yarn of unequal volume, laid upon a yarn-receiver.

35 3. In apparatus of the class described, a builder-motion, including an oscillating member having a constant stroke, and means carried by said member to control the builder-motion and through it effect automatically the formation of a preliminary winding with a short, uniform traverse, and a succeeding main winding with a long, uniform traverse, of yarn 40 upon a yarn-receiver.

45 4. In apparatus of the class described, a builder-motion, including an oscillating member, a single actuating device to impart a constant stroke thereto, and controlling means for the builder-motion carried by said member, to effect automatically the formation of two successive windings of yarn laid with the filling-wind upon a yarn-receiver.

5. In apparatus of the class described, a 55 builder-motion, including an oscillating member, a single actuating device to impart a constant stroke thereto, to lay yarn with the filling-wind upon a yarn-receiver, and means carried by said member to effect, when operative, an automatic change in the length of the traverse, whereby a portion of the yarn will be laid with a short traverse and the other portion with a long traverse.

6. In apparatus of the class described, a 65 builder-motion, including an oscillating mem-

ber having a constant stroke, and means carried by said member to control the builder-motion and through it effect automatically the formation of two successive windings of yarn upon a yarn-receiver, combined with means 70 to determine automatically the relative volume of said windings.

7. In apparatus of the class described, a builder-motion, including an oscillating member having a constant stroke, and means carried by said member to control the builder-motion and through it effect automatically the formation of two successive windings of yarn upon a yarn-receiver, constituting a bunch and a service-winding, combined with 80 manually-adjustable means to determine automatically the winding of the bunch and thereafter effect the change of traverse for the service-winding.

8. In apparatus of the class described, a 85 rotatable spindle, a yarn-receiver thereon, a builder-motion, including an oscillating member having a constant stroke, means carried by said member to control the builder-motion and through it effect the formation of a preliminary winding of yarn upon the yarn-receiver and thereafter a service-winding, and adjustable means to govern automatically the relative volume of said windings.

9. The combination, with a reciprocating 95 ring-rail, of a builder-motion, including a builder-arm, a single actuating device to impart a constant stroke thereto, connections between the builder-motion and the ring-rail, to control the movement of the latter, and means 100 carried by the builder-arm and acting through said connections, to change automatically from short to long traverse, to effect the winding of a bunch of yarn upon a yarn-receiver with the former, and to complete the service-winding with the latter, traverse.

10. The combination, with a reciprocating ring-rail, of a builder-motion, including a builder-arm, an actuating-cam to impart a constant stroke to said arm, connections between 110 the latter, and the ring-rail, to control the movement of the latter, and means carried by the builder-arm and acting through said connections to impart automatically a short traverse, and thereafter a long traverse, to the 115 ring-rail.

11. The combination, with a reciprocating ring-rail, of a builder-motion, including a builder-arm, a filling-wind-actuating device 120 therefor, connections between the builder-motion and the ring-rail, to control the movement thereof, and means carried by the builder-arm and operating through said connections to shift automatically from a short traverse to a long traverse at a predetermined and variable point in the winding, to thereby effect the formation of two windings of yarn upon a yarn-receiver, both laid with the filling-wind but with short and long traverse, respectively.

12. The combination, with a reciprocating 130

ring-rail, of a builder-motion, including a builder-arm, and a winding mechanism mounted thereon to govern the "gain" of the traverse, connections between the said mechanism and the ring-rail, to control the movement thereof, a traverse-cam to impart a constant stroke to the builder-arm, means carried by the latter to effect automatically the winding, with a short traverse, of a bunch of yarn upon a yarn-receiver, and thereafter the service-winding with a longer traverse, and separate devices to govern the "gain" for said windings through the winding mechanism.

13. The combination, with a reciprocating ring-rail, of a builder-motion, including a builder-arm, a single actuating device to impart a constant stroke thereto, connections between the builder-motion and the ring-rail, to control the movement of the latter, and traverse-shifting means carried by the builder-arm and including a short-traverse member movable with and also relatively to the builder-arm, to effect automatically reciprocation of the ring-rail with a short traverse through said member, and thereafter with full traverse corresponding to the stroke of the builder-arm.

14. The combination, with a reciprocating ring-rail, of a builder-motion, including a builder-arm, a single actuating device to impart a constant stroke thereto, connections between the builder-motion and the ring-rail, to control the movement of the latter, and traverse controlling or shifting means carried by the builder-arm, said means including a short-traverse member movable with and also relatively to the builder-arm, and mechanism to lock automatically said builder-arm and short-traverse member from relative movement, to effect when locked full traverse of the ring-rail, the short-traverse member moving relatively to the builder-arm when unlocked and effecting reciprocation of the ring-rail with a short traverse.

15. The combination, with a reciprocating ring-rail, of a builder-motion, including two pivotally-connected, rocking members movable in unison and also having a differential movement, a single actuating device to oscillate with a constant stroke one of said members, connections between the other member and the ring-rail, to reciprocate the latter, and means to effect automatically the coupling of said members to move in unison, differential movement of said members acting to lay a preliminary winding of yarn, with a short traverse, upon a yarn-receiver, and unison movement of said members, when coupled, acting to lay a service-winding with a long traverse.

16. The combination, with a reciprocating ring-rail, of a builder-motion, including two connected, rocking members movable in unison and also having a differential movement, a filling-wind-actuating cam directly coöper-

ating with and oscillating with a constant stroke one of said members, connections between the other member and the ring-rail, and means carried by the former member to couple automatically said members to rock in unison, differential movement of the members effecting reciprocation of the ring-rail with a short traverse and movement in unison when coupled effecting reciprocation with a full traverse, the former laying a bunch, and the latter a service-winding, of yarn upon a yarn-receiver.

17. The combination, with a reciprocating ring-rail, of a builder-motion, including two connected, rocking members movable in unison and also having a differential movement, an actuating-cam to oscillate the long-traverse member with a constant stroke, a winding mechanism on the other, or short-traverse member, to effect "gain" of the ring-rail, connections between said latter member and the ring-rail, to reciprocate the same, a fulcrum-dog on the short-traverse member, adapted to at times engage a fixed part of the apparatus, and thereby cause said member to rock relatively to the long-traverse member, to effect the winding of a bunch of yarn upon a yarn-receiver, automatic means to render inoperative the fulcrum-dog at the completion of the bunch and lock the two traverse members together to rock in unison, during the formation of the service-winding, and means actuated by winding back of the winding mechanism to uncouple the traverse members prior to the beginning of a new bunch-winding.

18. In apparatus of the class described, a ring-rail, a builder-motion, including a builder-arm, an actuating-cam to impart a constant stroke thereto, a traverse-shifter fulcrumed on the builder-arm, connections between the free end of said traverse-shifter and the ring-rail, to traverse the latter and govern the "gain" thereof, a fulcrum member about which the free end of the traverse-shifter is adapted to rock relatively to the builder-arm, to impart through said connections a short, uniform traverse to the ring-rail for a predetermined period, to form a bunch-winding of yarn upon a yarn-receiver, and means to thereafter couple the builder-arm and traverse-shifter to rock in unison and also release the traverse-shifter from the control of the fulcrum member, to thereupon impart a long, uniform traverse to the ring-rail and form a service-winding of yarn upon a yarn-receiver.

19. In apparatus of the class described, a ring-rail, a builder-motion, including a builder-arm having a fixed fulcrum, an actuating-cam for and to impart a constant stroke to said arm, a traverse-shifter pivotally connected at one end with said arm, a winding mechanism mounted on the free end of the traverse-shifter, a connection between said mechanism and the ring-rail, a fulcrum member for the

free end of and about which the traverse-shifter rocks relatively to the builder-arm during a predetermined number of oscillations thereof, to impart a short traverse to the ring-rail, and means operative automatically upon the completion of such number of oscillations of the builder-arm to render inoperative said fulcrum member and couple the traverse-shifter and builder-arm to rock in unison on the fixed fulcrum of the latter, to impart a long traverse to the ring-rail.

20. In apparatus of the class described, a ring-rail, a builder-motion, including a builder-arm having a fixed fulcrum, an actuating-cam for and to impart a constant stroke to said arm, a traverse-shifter pivotally connected at one end with said arm, a winding mechanism mounted on the free end of the traverse-shifter, a connection between said mechanism and the ring-rail, a fulcrum member for the free end of and about which the traverse-shifter rocks relatively to the builder-arm during a predetermined period, to impart a short traverse to the ring-rail, means to vary the length of the short-traverse period, and means operative automatically at the end of such period to render inoperative said fulcrum member and cause the traverse-shifter to rock in unison with the builder-arm on the fulcrum of the latter, to impart a long traverse to the ring-rail.

21. In apparatus of the class described, a ring-rail, a builder-motion, including a builder-arm having a fixed fulcrum, an actuating-cam for and to impart a constant stroke to said arm, a traverse-shifter pivotally connected at one end with said arm, a winding mechanism mounted on the free end of the traverse-shifter, a connection between said mechanism and the ring-rail, a fulcrum member for the free end of and about which the traverse-shifter rocks relatively to the builder-arm during a predetermined period, to impart a short traverse to the ring-rail, means to vary the length of the short-traverse period, and means operative automatically at the end of such period to render inoperative said fulcrum member and cause the traverse-shifter to rock in unison with the builder-arm on the fulcrum of the latter, to impart a long traverse to the ring-rail, combined with a device actuated by manual winding back of the winding mechanism to uncouple the builder-arm and traverse-shifter and permit the fulcrum member to assume control of the latter when beginning the next short-traverse period.

22. In apparatus of the class described, a ring-rail, a builder-motion, including a builder-arm having a fixed fulcrum, an actuating-cam for and to impart a constant stroke to said arm, a traverse-shifter pivotally connected at one end with said arm, a winding mechanism mounted on the free end of the traverse-shifter, a connection between said mechanism

and the ring-rail a fulcrum member pivoted 65 on the free end of the traverse-shifter and adapted when operative to engage a fixed part of the apparatus, to cause said traverse-shifter to rock relatively to the builder-arm and impart a short traverse to the ring-rail, a controlling-latch and a spring to move the fulcrum member into inoperative position, a latch-dog on the builder-arm, and means operative automatically at the end of the short-traverse period to move the said dog into 75 coöperation with the latch, to compress the spring and effect movement of the fulcrum member into inoperative position while coupling the traverse-shifter and builder-arm to rock in unison on the fulcrum of the latter, 80 to impart a long traverse to the ring-rail.

23. In apparatus of the class described, a ring-rail, a builder-motion, including a builder-arm having a fixed fulcrum, an actuating-cam 85 for and to impart a constant stroke to said arm, a traverse-shifter pivotally connected at one end with said arm, a winding mechanism mounted on the free end of the traverse-shifter, a connection between said mechanism and the ring-rail a fulcrum member pivoted 90 on the free end of the traverse-shifter and adapted when operative to engage a fixed part of the apparatus, to cause said traverse-shifter to rock relatively to the builder-arm and impart a short traverse to the ring-rail, a controlling-latch and a spring to move the fulcrum member into inoperative position, a latch-dog on the builder-arm, and means operative automatically at the end of the short-traverse period to move the said dog into 100 coöperation with the latch, to compress the spring and effect movement of the fulcrum member into inoperative position while coupling the traverse-shifter and builder-arm to rock in unison on the fulcrum of the latter, 105 to impart a long traverse to the ring-rail, combined with a resetting-pawl connected with the latch-dog, and an actuating-cam for the pawl, operated by or through winding back 110 of the winding mechanism, to effect release of the latch by the latch-dog and thereby uncouple the traverse-shifter and builder-arm and permit the fulcrum member to assume its operative position at the beginning of the next 115 short-traverse period.

24. In a machine of the class described, a builder-motion, including two members adapted to swing in unison about a common fulcrum to effect the formation of a service-winding of yarn upon a yarn-receiver, said members 120 being adapted to swing on separate fulcrums to effect the formation of a bunch-winding on the yarn-receiver, controlling means to automatically lock said members to swing in unison at the end of the bunch-winding period, 125 and a traverse-cam to coöperate with and cause one of said members to oscillate with a constant stroke about the fulcrum common to

both members, the service-winding being laid with a corresponding long traverse and the bunch-winding with a short traverse.

25. In apparatus of the class described, a 5 ring-rail, a builder-motion, including a builder arm rocked with a constant stroke, a traverse-shifter pivoted on said arm, to transform the stroke thereof to a shorter stroke during the formation of a preliminary winding of yarn 10 upon a yarn-receiver, connections between the traverse-shifter and the ring-rail, means to couple the traverse-shifter and builder-arm to rock in unison with the longer stroke of the latter to complete the main or service winding, and 15 mechanism to operate the coupling means and govern the volume of the preliminary winding, said mechanism including a rotatable controller, a device to rotate it step by step during preliminary winding, the total angular 20 movement of the controller determining the number of layers of yarn to be laid in such winding, an actuator for the coupling means, and a detent to maintain the actuator inoperative, said detent being released by the controller 25 when its predetermined angular movement has been attained.

26. In apparatus of the class described, a reciprocating ring-rail, means to effect its traverse, including an arm rocked with a constant 30 stroke, a traverse-shifter interposed between the ring-rail and said arm, connected with and actuated by the latter, to effect a short, uniform traverse of the ring-rail to wind a bunch of yarn upon a yarn-receiver, and there- 35 after when moving in unison with the arm to effect a long, uniform traverse to complete the service-winding of the yarn; means to lock the traverse-shifter and arm, including a member 40 slidable on the latter; and mechanism to operate said means and to govern the volume of the bunch, said mechanism, including a ratchet having a releasing-pin, a pawl to rotate the ratchet step by step during bunch-winding, an actuator to operatively move the 45 slidable member of the locking means, and a detent to maintain the actuator inoperative and located in the path of the releasing-pin, the total angular movement of the pin from the initial position to engagement with and 50 release of the detent determining the number of layers of yarn in the bunch, movement of the slidable member by the released actuator causing the traverse-shifter and rocking arm to be locked for movement in unison.

27. In apparatus of the class described, a reciprocating ring-rail, a builder-motion, including a builder-arm and a traverse-shifter fulcrumed thereon, a traverse-cam to rock the arm with a constant stroke, a connection be- 55 tween the traverse-shifter and ring-rail, a ful- 60 crum member about which the traverse- shifter is swung by relative movement of the builder-arm during the formation of a preliminary winding of yarn upon a yarn-re- 65 ceiver; means to prevent relative movement

of the shifter and arm during the formation of the main winding, including a latch on one and a sliding dog on the other of said members, and means operated by movement of the arm during the preliminary winding to determine the volume thereof, and to effect co-operation of the latch and dog at the termination of said winding, such co-operation effecting the inoperative positioning of the fulcrum member. 70

28. In apparatus of the class described, a reciprocating ring-rail, a builder-motion, including an arm oscillated with a constant stroke, and a traverse-shifter pivoted at one end on the arm and swung by oscillation thereof about a fulcrum at its free end during the formation of a preliminary winding of yarn upon a yarn-receiver; a connection between the traverse-shifter and ring-rail, to reciprocate the latter; locking means to prevent relative movement of the shifter and arm during the formation of the service-winding; adjustable mechanism to predetermine the volume of the preliminary winding and govern the operation of the locking means, said mechanism including a detent for the locking means, an actuator for the latter, and a device to automatically release the detent when the preliminary winding has attained the predetermined volume; and separate means to return 95 the locking means to inoperative position under control of the detent after completion of the service-winding and prior to beginning a new preliminary winding. 90

29. In apparatus of the class described, a reciprocating ring-rail, a builder-arm oscillated with a constant stroke, a traverse-shifter pivoted at one end on said arm, winding mechanism mounted on the shifter; a connection between said mechanism and the ring-rail, to reciprocate the same; a resetting-cam rotatable with the drum of said mechanism; a two-part, spring-connected latch-dog slidable on the arm and having a pawl to at times co-operate with said cam; a latch on the traverse-shifter, to lock the latter and the arm to move in unison when the latch and latch-dog co-operate; a fulcrum member on the free end of the shifter and about which it rocks to effect the formation of a bunch of yarn, with a short traverse, on a yarn-receiver when said arm and shifter are unlocked; connections between the fulcrum member and the latch, to render the former inoperative when the latter co-operates with the latch-dog; means carried by the builder-arm to lock the traverse-shifter thereto when a predetermined volume of yarn has been wound in the bunch, the movement of the locked members thereafter effecting the formation of the service-winding 115 with a long traverse, manual winding back of the winding mechanism acting through the resetting cam and pawl to render the latch-dog inoperative prior to the beginning of the next bunch-winding, and a manually-operated 120 125 130

device to depress the ring-rail for doffing, the spring connection between the parts of the latch-dog permitting said parts to separate temporarily if winding back is effected 5 before the ring-rail is depressed by the said manually-operated device.

In testimony whereof I have signed my name

to this specification in the presence of two subscribing witnesses.
